PORTABLE EXERCISING DEVICE OR SIMILAR ARTICLE

Whitney Hastings, Middletown, Conn.

Application December 23, 1957, Serial No. 48,989

Term of patent 14 years

(Cl. D34—5)

Fig. 1

Fig. 3

Fig. 1 is a front elevational view of a portable exercising device or similar article showing my new design; Fig. 2 is a view thereof in side elevation; and Fig. 3 is a top plan view.

I claim:

The ornamental design for a portable exercising device or similar article, substantially as shown.
